DESIGN FOR A BEACH COAT OR SIMILAR ARTICLE

Leonard C. Asch, New York, N. Y., assignor of one-half to Polly Prentiss, Inc., Sumter, S. C., a corporation of South Carolina, and one-half to Asbury-Prentiss, Inc., Sumter, S. C., a corporation of New York

Application April 27, 1939, Serial No. 84,640

Term of patent 3½ years

To all whom it may concern:

Be it known that I, Leonard C. Asch, a citizen of the United States, residing at New York, in the county of New York and State of New York, have invented a new, original, and ornamental Design for a Beach Coat or Similar Article, of which the following is a specification, reference being had to the accompanying drawing, forming a part thereof.

The characteristic feature of my design resides in the specific fish and bubble elements applied on each side of the front of the beach coat disclosed or other similar article, in association with the specific fish and bubble elements on the back thereof, as shown.

I claim:

The ornamental design for a beach coat or similar article, substantially as shown and described.

LEONARD C. ASCH.
